UNITED STATES PATENT OFFICE.

WILLIAM H. DAILY, OF LOS ANGELES, CALIFORNIA.

PHONOGRAPH.

Application filed May 24, 1923. Serial No. 641,091.

This invention relates to automatic phonographs, and more especially to phonographs of the general type including a multiplicity of record-carrying tables, such for instance, as are shown in my Patent Number 1,168,606, dated January 18, 1916, and in my allowed application Serial Number 577,324, filed July 25, 1922, for automatic multiple record phonographs.

The principal object of my present invention is to provide improvements in the driving mechanism, and more particularly to provide a combined multiple table phonograph and induction meter type motor all in one organized structure in which the motor is provided with an armature ring presented and running in juxtaposition to induction coils.

Another object is to provide means for readily varying the number of rotations of the record-carrying tables without changing the speed of the motor armature. Another object is to provide a multiple table phonograph in which means are provided for progressively shifting the tone arm and the sound box from one applied record to another, and to provide a motor including a rotary element operative to selectively drive the respective tables and also to drive a mechanism operative to swing the tone arm from table station to table station. An object is to provide means for defining the position of the tone arm accurately as to records of the usual standard sizes, and, in this connection, an object is to provide means for preventing a reverse swinging of the tone arm accidentally or otherwise from its properly disposed position preparatory to the stylus being engaged by a contiguous record.

An object is to provide an improved means for rendering the tone arm carrier inoperative so that any one of the turn-tables may be continuously rotated for any desired length of time, and without a swinging of the tone arm from table to table.

Other objects and advantages will be made manifest in the following specification of an embodiment of the invention illustrated in the accompanying drawings, wherein—

Figure 1 is a plan of the improved phonograph.

Fig. 2 is a side elevation and vertical section (substantially full size) of the tone arm,

and a portion of one of the tables and the tone arm swinging mechanism; the tone arm being in elevated position and the stylus engaging a ten-inch record.

Fig. 3 is a detail elevational view showing the tone arm leg and toe supported on a tone arm carrier, and in stopped position engaging a positioning lug of an arrester.

Fig. 4 is a vertical section and elevational view showing the change gear shift device in low speed position taken on the line 4—4 of Fig. 1.

Fig. 5 is a vertical section through parts of the apparatus, which is on full size scale, and shows a turn-table as elevated and in driving engagement with the motor rotor-armature taken on line 5—5 of Fig. 1.

Fig. 6 is a plan and horizontal section taken substantially on line 6—6 of Fig. 5 showing the cam sector and an adjustable cam tripper which determines the period of cooperation between the tone arm and a disc record according to the actual length of the record groove.

Fig. 7 is an elevation and sectional detail view showing the table elevating cam in position about to engage a table spindle.

Fig. 8 is a detail, vertical section showing a brake means taken on line 8—8 of Fig. 9.

Fig. 9 is a plan showing a speed governor.

Fig. 10 is a plan showing the cam sector and the set of adjustable cam trippers.

Fig. 11 is a vertical sectional view of a portion of the apparatus, and clearly showing the pivotal mounting of the tone arm taken on line 11—11 of Fig. 1.

Fig. 12 is a plan showing, diagrammatically, fragments of adjacent tables with twelve-inch records applied; the tone arm toe being shown in arrested position before the elevation of the subjacent record, and clearly showing the adjustable arrester in low speed position for large records, ten-inch records being indicated by dotted lines.

Fig. 13 is a plan of a fragment of the arrester showing it disposed in neutral or drive cut-out position.

Fig. 14 is a plan and horizontal section showing a fragment of the arrester in a high speed position for playing short or small records.

Fig. 15 is a vertical section showing a portion of the machine frame with sets of

motor coils provided thereon and with the rotor-armature having a position between opposed coils of the sets.

Fig. 16 is a plan of the machine showing only one record turn-table.

Fig. 17 is a detail elevation showing the tone arm foot resting on the carrier, and

Fig. 18 is a detail showing the tone arm leg and foot in uplifted position engaging the positive tone arm stop guard.

In the machine of my present invention, phonograph records, here shown as discs D, are adapted to be mounted on turn tables which are adapted to be rotated substantially at a uniform rate of speed, and yet provide means for automatically interrupting the operative engagement between a disc D and the stylus S according to the size of the record disc and according to the length of its record groove. The means for determining the operative co-action between a disc D and the stylus includes a two-speed gear mechanism selectively operative to drive the means for lifting a record disc to engage the stylus of the tone arm T; said means including a member which is designed to move at a given rate when a large disc is being played, and to move at a faster rate when a small disc is being played, since the smaller discs require an appreciably shorter length of time while they are engaged by the tone arm stylus than do the larger discs.

The invention is shown as embodied in a machine having a plurality of vertical spindles 2, which are appropriately journaled in bearings 3 and 4, which may form a part of a skeleton frame structure, the various portions of which are designated at 5; the frame components being of substantially cylindrical form and including upper and lower ring portions which are connected as by webs 5^a. The spindles extend substantially vertically and each is provided with a turn-table 6; the spindles being arranged in a common circle and designed to rest upon contiguous bearings, so that the tables are, when at rest, in a common plane, and the tables are designed to receive, in the usual manner, phonographic record discs D which, for the purposes of the present exposition, may be considered as of ten and twelve inches diameter in different sizes.

Arranged in the geometrical center of the group of turn tables is a vertical tone arm column 7, which is appropriately secured in the frame, and this has, at its upper portion, a suitable bearing to receive the contiguous end of the tone arm T which carries the sound box B; the tone arm being pivoted on the top of the column 7 to freely swing around the same, and being also pivoted upon a horizontal, transverse axis on a swinging spider 7^a, so that the outer end of the

tone arm may be raised and lowered in a manner to be subsequently described. The column 7 forms a continuation of the sound tube leading to any horn or other amplifying outlet chamber, not here shown.

The tone arm T is provided with a downwardly extending leg 8, which has at its lower end a substantially radially projecting foot 10 and a rounded heel 9 which is normally supported on the top of a rotating carrier 12, surrounding the column 7 and rotating thereabout. The carrier 12 is in the form of a plate or flat ring and is fixedly attached to a gear 13, disposed below the carrier 12 and resting on and countersunk in the frame part 5.

Extending from the top bearing portion 5, Figure 5, is a vertical bearing 15, in which there is disposed a shaft 16, to the upper end of which is secured a pinion 17, which engages an intermediate gear 18, meshing with and driving the carrier gear 13. The shaft 16 is provided with an upper gear wheel 16^a, meshing with a gear 20, forming a portion of or secured on a sleeve 21, upon the lower end of which is secured an element which, in the present case, forms a rotor-armature including the hub 22, secured on the sleeve 21, and a peripheral flat armature ring 22^a; this element constituting the prime driving, motor element of the mechanism.

Also secured on the sleeve 21, which substantially constitutes the motor shaft, is a gear 23, of larger diameter than the gear 20, and engaging a gear 24, of smaller diameter than the gear 16^a, and which is loosely mounted on the lower end portion of the shaft 16. Means are provided for selectively coupling either gear 16^a or 24 to the shaft 16, and this means includes a clutch collar 25, splined on the shaft 26 and the ends of which are adapted to engage complementary clutch portions 25^a, on the gear 16^a, and 25^a on the gear 24, so that the shaft 16 can be driven at either of two speeds.

The rotor-armature is shown as provided with an anti-friction, lower end bearing 32, surrounding an inner hollow shaft 29, on which the hollow motor shaft 21 is loosely mounted. The hollow shaft 29 is provided at its upper end with a worm wheel 28, and this is constantly in mesh with a worm pinion 27, formed with or provided on a worm shaft 27^a, horizontally journaled in a bearing portion 5 below the carrier plate 12, and being provided with a bevel pinion 27^a engaging and being driven by a bevel pinion 16^a, secured on the upper end of the shaft 16.

Therefore, when the rotor-armature or driving member 22 is operating, as will be hereinafter described, it drives the selected gear 16^a or 24 and this, in turn, drives the shaft 16 which, therefore, concurrently

drives the carrier 12 at a very slow rate of movement, and also drives the worm wheel 28 and the inner, hollow shaft 29.

The hollow shaft 29 passes through and forms a bearing for the sleeve 21, and on the lower end of the hollow shaft there is secured in any suitable manner, as by threads 29', the hub 30 of a tripping device which, in the present form, includes a sector plate 31, Figure 6. On the hub 30 is provided the anti-friction bearing 32, and upon this rests the hub of the rotor-armature 22 of the sleeve 21.

The rotor armature is provided with a horizontally arranged, turn-table, driving rim or face 34, of any suitable construction, and which preferably is of an efficient friction producing element such as a band or ring of leather or rubber. This driving rim 34 is for the purpose of forming a common driver for the driving wheels 2^a of each of the turntable spindles 2, when the spindles are elevated so as to bring the friction wheels 2^a against the driving rim 34.

The various record turn-tables 6 are adapted to be raised from a normal position in a common plane to an effective, raised position to lift the records successively into engagement with the needle or stylus in the sound box. The tone arm and the sound box move constantly in a fixed, horizontal plane, while being supported by the rotating carrier 12. However, it is possible to lift the tone arm on a horizontal axis during the operation of the parts.

The tone arm carrier rotates at a given rate of speed so as to swing it from one disc to another in ample time to be positioned above the disc on each table before the table is elevated. Since it is possible to utilize two sizes of discs D on the tables, it is necessary to provide means for accurately defining the stopping position of the tone arm at predetermined locations, so that it will properly register with the starting curve of a disc of either size. To that end, my present invention includes an improved form of positioning means.

In this machine, there is disposed upon the top, central portion of the frame and below and projecting beyond the edge of the carrier 12, an adjustable arrester in the form of a flat ring 40^a, provided with a set of upwardly projecting lugs or dogs 40, which are arranged in a common circle on the top of the arrester ring and so disposed as to stand in the path of the outer or toe end of the foot portion 10 of the tone arm leg 8, which is designed to successively engage the fixed dogs 40 as the tone arm is swung around by the carrier in the direction of the arrow thereon, Figure 12. The arrester ring is designed to be turned on its own axis so that the dogs 40 will

arrest the tone arm in an outer position as to the table center to properly engage the starting record groove of a twelve-inch record, and is also adapted to be adjusted so that the dogs 40 will serve to arrest the swinging movement of the tone arm by the carrier 12 to properly position the sound box stylus at the starting groove of a smaller or ten-inch record. To that end, the arrester 40^a is shown as provided with a radially extending fork 40^b to receive a segmental cam 41, which is secured on a setting stem 42, Figure 4, journaled in an arm of the frame 5 and having at its upper end a readily accessible thumb wheel 43, by which it may be turned to rotate the arrester according to the size of records to be played. The stem is provided with an index wheel 44, appropriately marked to designate neutral position in the fork 40^b, and also marked "12" and "10" in correspondence with ten and twelve-inch records.

When the setting wheel and its indicator 44 are turned in one position, as shown in Figure 12, the arrester dogs 40 are set so as to engage the tone arm foot 10 at such a position in its orbit as to arrest the tone arm to position the needle of the sound box over the starting groove of a twelve-inch record. It is understood that all of the records positioned at one time on the machine must be of equal size. When playing small records, the setting stem 42 is shifted so as to throw the arrester and the dogs 40 through a small arc about the center of the tone arm and arrester to a position whereat the dogs 40 will permit the tone arm to swing nearer to the centers of the turn tables and thus be properly positioned to start the playing of small records. The arrester ring 40 is shown as provided with a slot 40^c, into which projects a stop pin 40^d to limit the movement in either direction of the arrester. The adjusting cam 41 may be stopped as by a stop pin 45, Figure 13.

For the purpose of preventing a backward swinging of the tone arm from its raised position against a stop lug or dog 40, as the tone arm may be lifted, there is disposed adjacent each of the dogs a backstop or rest 46, spaced just sufficiently from the dog to receive the projected and uplifted toe end of the foot 10, as is clearly shown in Figure 2; the backstops 46 being of a height slightly greater than the dogs over which the foot portion is adapted to move as the tone arm is automatically swung in toward the center of a disc which is cooperatively engaged for a playing period.

The setting stem 42 provides means not only for adjusting the arrester 40^a, but it also provides means for shifting the gear shift or change device 25. On the lower

end of the setting stem 42 is secured a screw or provided a threaded portion 47, upon which is slidably mounted a hub 48 of a clutch shift arm 49, the opposite end of which engages the clutch member 25. The hub is shown as provided with a pin or screw 48^a, engaging the thread or groove of the part 47 and therefore, when the setting stem 42 is rotated, the hub is shifted 10 up or down and the clutch member 25 is correspondingly shifted so as to lock one or the other of the gear wheels 16^a—24 to the countershaft 16.

This change speed device provides for the 15 change of speed of the quadrant 31, which forms a part of means for timely elevating the successive turn-tables.

The tables are elevated in the following manner: The lower end of each spindle 2 20 is designed to bear against a cam including a rail 50 of segmental form having an elevating, leading cam or inclined face 50^a. This cam rail, in my present invention, is mounted for pivotal action adjacent its forward 25 cam end 50^a on a pivot pin 51, provided on the cam sector 31, and its rear end portion is yieldingly drawn inwardly, on top of the sector 31, as by a spring 52. The cam sector 31 is substantially continuously driven 30 in the direction of the arrow thereon in Figure 6, and the cam rail 50 is adapted to be swung from a retracted position to an outer, effective or set position at predetermined intervals during its orbital movement, and for thus shifting the cam rail 50 outwardly and to a substantially concentric position as to the axis of the tone column, a portion of the cam rail 50 has a shoe 50^b with an inclined leading end 50^c, which is 40 designed to be successively brought into engagement with stationary cam setting means which may consist of a simple and substantially downwardly projecting or otherwise arranged cam setting tongue or lug 53, Figures 6 and 11, and of which there are 45 as many as there are turn-tables or turn-table stations in the machine.

Thus, as the cam sector 31 slowly sweeps 50 in its horizontal orbit, the shoe end 50^c engages an interposed, stationary setting tongue 53, and the cam rail 50 is thrown to the outer, effective, concentric position so as to be disposed below and pass under, engage and lift a turn-table spindle 2; the approaching position of the cam being indicated clearly in Figure 7. Upon co-action or engagement between the lifting cam rail 50 and the contiguous turn-table spindle 2, the spindle is elevated and maintained in a substantially unvarying position as the top, plane face of the cam 50 continues in its circular orbit, until such predetermined time as may be necessary to trip or interrupt the co-action between the cam and the engaged turn-table spindle, this being deter-

mined by the length of the record groove on the engaged phonographic record disc.

Means are provided and adapted to be manually adjusted for automatically, reliably, effectively and substantially instantaneously tripping the cam 50 from an engaged turn-table spindle 2, substantially concurrently with the reaching of the stylus of the sound box with the end of the record groove, so that the table and record will be withdrawn from effective or elevated, playing position and the record disengaged from the stylus. A simple form of cam tripping means is here shown as including a set of radial tripper arms 55, the hubs of which 80 are mounted loosely upon the hub 30 of a cam sector 31, and below the anti-friction bearing 32. Each tripper arm 55 is provided with a segmental gear 56, which is supported for convenience in a groove 57, 85 provided in a bottom ring of the frame 5, as clearly shown in Figures 5 and 11.

There is one tripper arm 55 for each turn-table station, and these arms are disposed relatively in advance of the turn-table stations so that the tripper arms 55 can be properly positioned and cause the tripping of the cam 50 or its withdrawal from the engaged and elevated turn-table stem at the proper moment. Each segmental gear 56 is 90 engaged by a setting wheel 58, secured on a setting spindle 59, for which suitable bearing portions 5^b of the frame 5 are provided. The upper ends of the trip setting spindles 59 are provided with thumb wheels 60, and 95 below these are dials 61, indexed according to any arbitrary system adopted and used to indicate a corresponding index applied to the various record discs according to the terminating position of the record groove. 100 Having a given record groove index, it is only necessary to set the indicating spindles 61 with respect to any suitable index mark according to the given index of a selected record disc and by the manipulation of the 105 index or setting spindle 59, the respective tripping devices will be properly set to cause the disengagement of the respective cam from the engaged turn-table spindle. The actual tripping is determined by a let-off lug or projection 55^a, provided on the lower side of each tripping arm 55. When the cam 50 is thrown to the effective setting position by the engaged setting tongue 53, the cam shoe 50^b, which has an arcuate, inner edge, passes freely along the outside of the let-off tongue 55^a, while the cam sector 31 is slowly sweeping around. As soon as the tail end of the shoe 50^b passes the let-off tongue 55^a, as shown in Figure 6, then 115 the cam retracting spring 52 instantly acts to retract the cam 50 and pull it inwardly from supporting relation below the engaged turn-table spindle 2, and the latter then drops and brings down with it its re- 120

spective table 6, the downward movement of the latter being cushioned and determined as by a cushioning washer 6^a, Figure 5, when the latter falls to engagement with 5 the upper bearing 3 thereof.

It will be seen that each of the cam tripping arms can be independently adjusted in direct accordance with the actual length of the record groove on a record applied to 10 a coordinate turn-table. In operation of the machine, the cam 50 is moved to an outer or set position at each turn-table station by the reaction of the cam setting tongues 53, and these hold the engaged cam in outer, 15 set position until it is engaged and supported by the let-off tongue 55^a of the cam tripping lever arm 55.

The cam 50 is stopped in its inward or retracted position by any suitable stop, as 20 a lug 31^a, provided on the top of the cam sector 31.

Any suitable governing means may be employed to regulate the speed of rotation of the turn-tables, and a simple form is shown 25 as including a centrifugal governor 70, having a worm screw 71, engaging the worm wheel or ring 72, formed or secured on a sleeve or hollow shaft 21, in the present case being shown as disposed between the gear 30 portions 20—23. The centrifugal governor is provided with a disc 73, movable toward a brake shoe 75, Figure 9. The brake shoe is shown in Figure 8 as being mounted on a lever 76, connected to a spring 77, suitably 35 attached to a fixed part. The brake lever 76 is engaged by an adjusting screw 78, which may be turned to advance the brake shoe 75 toward the brake disc 73 of the governor, and therefore increase the resistance 40 as the motor reaches a predetermined speed.

The above specification, it will be seen, sets forth, first, the operating train, and the several automatically acting mechanisms of the phonograph. A feature of the invention is 45 the provision of a novel prime motor including the rotor-armature 22—22^a, above referred to, which serves as the principal driving means whereby all the turn-tables and other elements of the machine are actuated.

50 The motor of this machine is of the well known, highly efficient, practicable, simple, and reliably acting induction meter type of motor, in which there are utilized suitable induction coils diagrammatically illustrated 55 as arranged in opposition at 80 and 80^a, Figure 15, the coils of each set being spaced to receive the armature ring 22^a which operates, therefore, rotatively between the coils of each set in the usual and well known manner of 60 this type of motor. The several sets of coils 80—80^a are arranged, in the present case, in upright position along the inside faces of the ring components of the frame 5.

65 It is to be understood that this organized phonographic mechanism and self-con-

tained motor are adapted to be erected as a complete, unitary system, and mounted in any suitable manner in any desired form of cabinet or other support.

The turn-tables operate, when engaged 70 by the rotor-armature, at a substantially constant rate of speed, which is not changeable by the gear shift device including the clutch member 25; the latter being for the purpose of regulating and changing the 75 speed of travel of the cam segment 31 according to whether a large or small disc is being run. If a large disc is being played, then the gear shift is set so that the cam is driven slowly, while if a small disc is being played, 80 the gear shift is set so that the cam will drive faster.

The mechanism of the apparatus is shown in Figure 16 as covered by a top plate 85, and this is provided with a central opening 85 86, through which is exposed upwardly projecting arrester lugs 40 and 46, so that these will be in effective position to engage the tone arm foot portion 10. As the tone arm is thrown to the inner position of a record, 90 as shown in Figure 16, the arm is positively limited against an inward sweeping movement across the disc by guards shown as consisting of upwardly extending lugs 87, positioned around the edge of the opening 95 86 and so disposed as to intercept the toe end of the foot 10 when the tone arm is elevated to effective position, and the end of the toe is swinging in a circle in which the stop guard lugs 87 are positioned. As soon 100 as the turn-table is tripped, the tone arm descends until its foot engages the carrier 12, and in this action, the toe of the foot 10 drops clear of the stop guard 87, as is shown in Figure 17, so that the tone arm can be 105 swung to the next station as soon as the subjacent record and turn-table have been lowered; the stylus of the sound box on the tone arm sweeping, in its lowered position, in a plane above the plane of the normal lowered 110 records.

Further embodiments, modifications and variations may be resorted to within the principle of the invention.

What is claimed is:

1. A phonograph having, in combination, 115 a plurality of rotary record supports, a friction wheel to rotate each support and a single induction motor including a single rotor-armature formed of an annulus attached to a central friction driving ring to drive each friction wheel and thence the plurality of supports.

2. A phonograph having, in combination, 125 a plurality of rotary record supports, a friction wheel to rotate each support, an induction motor including a rotor-armature formed of an annulus attached to a central friction driving ring to drive each friction wheel and thence the supports, and a tone 130

- arm driven from support to support by the said rotor-armature.
3. A phonograph having, in combination, a plurality of rotary record supports, a friction wheel to rotate each support, and an induction motor including a rotor-armature formed of an annulus attached to a central friction driving ring to drive each friction wheel and thence the supports, the induction motor forming a self-contained, prime mover for the phonograph mechanism.
4. A phonograph having, in combination, a plurality of rotary record supports, a friction wheel to rotate each support, an induction motor including a rotor-armature formed of an annulus attached to a central friction driving ring to drive each friction wheel and thence the supports, a tone arm driven from support to support by the said rotor-armature, and a change speed gear mechanism including a carrier for the tone arm and which is driven by the rotor-armature.
5. A phonograph having, in combination, a plurality of rotary record supports, a friction wheel to rotate each support, and an induction motor including a rotor-armature formed of an annulus attached to a central friction driving ring to drive each friction wheel and thence the supports, said supports being independently driven by the rotor-armature.
6. A phonograph having, in combination, a plurality of rotary record supports, a friction wheel to rotate each support, an induction motor including a rotor-armature formed of an annulus attached to a central friction driving ring to drive each friction wheel and thence the supports, said supports being independently driven by the rotor-armature, and means for shifting the supports into effective cooperation with the rotor-armature.
7. A phonograph having, in combination, a plurality of rotary record supports, a friction wheel to rotate each support, an induction motor including a rotor-armature formed of an annulus attached to a central friction driving ring to drive each friction wheel and thence the supports, means for successively elevating the supports so as to shift a record into engagement with a stylus carried by the tone arm of the phonograph, and driving connections between the rotor-armature and the said means.
8. A phonograph having, in combination, a plurality of rotary record supports, a friction wheel to rotate each support, an induction motor including a rotor-armature formed of an annulus attached to a central friction driving ring to drive each friction wheel and thence the supports, variable speed means for successively elevating the supports so as to shift a record into engagement with a stylus carried by the tone arm
- of the phonograph, and driving connections between the rotor-armature and the said means.
9. A phonograph having, in combination, a plurality of rotary record supports, a friction wheel to rotate each support, an induction motor including a rotor-armature formed of an annulus attached to a central friction driving ring to drive each friction wheel and thence the supports, manually controlled, speed changing means for successively elevating the supports so as to shift a record into engagement with a stylus carried by the tone arm of the phonograph, and driving connections between the rotor-armature and the said means.
10. A phonograph having, in combination, a plurality of rotary record supports, a friction wheel to rotate each support, an induction motor including a rotor-armature formed of an annulus attached to a central friction driving ring to drive each friction wheel and thence the supports, variable speed means for successively elevating the supports so as to shift a record into engagement with a stylus carried by the tone arm of the phonograph, and driving connections between the rotor-armature and the said means.
11. A phonograph having, in combination, a plurality of rotary record supports, a friction wheel to rotate each support, an induction motor including a rotor-armature formed of an annulus attached to a central friction driving ring to drive each friction wheel and thence the supports, means for successively elevating the supports so as to shift a record into engagement with a stylus carried by the tone arm of the phonograph, and driving connections between the rotor-armature and the said means, said elevating means being operative to sustain a record support for a period determined according to the length of the record groove.
12. A phonograph having, in combination, a plurality of rotary record supports, a friction wheel to rotate each support, an induction motor including a rotor-armature formed of an annulus attached to a central friction driving ring to drive each friction wheel and thence the supports, means for successively elevating the supports so as to shift a record into engagement with a stylus carried by the tone arm of the phonograph, driving connections between the rotor-armature and the said means, said elevating means being operative to sustain a record support for a period determined according to the length of the record groove, and manually adjustable means for controlling the release of the record support at a predetermined moment.
13. A phonograph having, in combination,

a plurality of rotary record supports, a friction wheel to rotate each support, an induction motor including a rotor-armature formed of an annulus attached to a central friction driving ring to drive each friction wheel and thence the supports, orbitally movable means for successively elevating the supports so as to shift a record into engagement with a stylus carried by the tone arm of the phonograph, and driving connections between the rotor-armature and the said means.

14. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables, and driving means for the turn-tables comprising friction wheels adapted to be individually engaged and driven by a friction driving wheel attached to the rotor-armature.

15. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables, and driving means for the turn-tables comprising friction wheels adapted to be individually engaged and driven by a friction driving wheel attached to the rotor-armature, the record turn-tables being provided with axially movable spindles each having a driving wheel, and means for shifting the driving wheels into engagement with the rotor-armature.

16. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables, and driving means for the turn-tables comprising friction wheels adapted to be individually engaged and driven by a friction driving wheel attached to the rotor-armature, the record turn-tables being provided with axially movable spindles each having a driving wheel, and means for selectively shifting the driving wheels into engagement with the rotor-armature.

17. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables mounted on the frame, and driving means for the turn-tables comprising

friction wheels adapted to be individually engaged and driven by a friction driving wheel attached to the rotor-armature.

18. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables, and driving means for the turn-tables comprising friction wheels adapted to be individually engaged and driven by a friction driving wheel attached to the constant speed rotor-armature. 80

19. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables, driving means for the turn-tables comprising friction wheels adapted to be individually engaged and driven by a friction driving wheel attached to the constant speed rotor-armature, and a tone arm having a stylus to engage a record on each turn-table, said tone arm sweeping in an orbit on the axis of the rotor-armature. 95

20. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables, driving means for the turn-tables comprising friction wheels adapted to be individually engaged and driven by a friction driving wheel attached to the constant speed rotor-armature, a tone arm having a stylus to engage a record on each turn-table, said tone arm sweeping in an orbit on the axis of the rotor-armature, and means driven by the rotor-armature of the self-contained motor for carrying the tone arm from one turn-table station to another. 110

21. A self-contained motor phonograph including a frame provided with a plurality of sets of motor induction coils, the coils of each set being spaced, a rotor-armature having an armature portion to sweep in the gaps between the spaced coils of the motor magnets, a plurality of record-supporting turn-tables, driving means for the turn-tables comprising friction wheels adapted to be individually engaged and driven by a friction driving wheel attached to the constant speed rotor-armature, a tone arm having a stylus to engage a record on each turn-table, said tone arm sweeping in an orbit on the axis of the rotor-armature, and means driven by the rotor-armature of the self-contained motor for progressively carrying 130

the tone arm from one turn-table station to another.

22. A self-contained motor phonograph including a frame provided with a plurality of sets of motor induction coils, the coils of each set being spaced, a rotor-armature having an armature portion to sweep in the gaps between the spaced coils of the motor magnets, a plurality of record supporting turn-tables, driving means for the turn-tables comprising friction wheels adapted to be individually engaged and driven by a friction driving wheel attached to the rotor-armature, and a rotary means for successively elevating the record turn-tables to bring the records thereon into engagement with the stylus of the phonograph.

23. A self-contained motor phonograph including a frame provided with a plurality of sets of motor induction coils, the coils of each set being spaced, a rotor-armature having an armature portion to sweep in the gaps between the spaced coils of the motor magnets, a plurality of record supporting turn-tables, driving means for the turn-tables comprising friction wheels adapted to be individually engaged and driven by a friction driving wheel attached to the rotor-armature, a rotary means for successively elevating the record turn-tables to bring the records thereon into engagement with the stylus of the phonograph, and a driving connection between the rotor-armature and the said elevating means.

24. A self-contained motor phonograph including a frame provided with a plurality of sets of motor induction coils, the coils of each set being spaced, a rotor-armature having an armature portion to sweep in the gaps between the spaced coils of the motor magnets, a plurality of record supporting turn-tables, driving means for the turn-tables comprising friction wheels adapted to be individually engaged and driven by a friction driving wheel attached to the rotor-armature, a rotary means for successively elevating the record turn-tables to bring the records thereon into engagement with the stylus of the phonograph, and a variable speed driving connection between the rotor-armature and the said elevating means.

25. A self-contained motor phonograph including a frame provided with a plurality of sets of motor induction coils, the coils of each set being spaced, a rotor-armature having an armature portion to sweep in the gaps between the spaced coils of the motor magnets, a plurality of record supporting turn-tables, driving means for the turn-tables comprising friction wheels adapted to be individually engaged and driven by a friction driving wheel attached to the rotor-armature, a rotary means for successively elevating the record turn-tables to bring the records thereon into engagement with the

stylus of the phonograph, and a variable speed driving connection between the rotor-armature and the said elevating means, said variable speed mechanism not affecting the speed of the motor rotor-armature.

26. A self-contained motor phonograph including a frame provided with a plurality of sets of motor induction coils, the coils of each set being spaced, a rotor-armature having an armature portion to sweep in the gaps between the spaced coils of the motor magnets, a plurality of record supporting turn-tables, driving means for the turn-tables comprising friction wheels adapted to be individually engaged and driven by a friction driving wheel attached to the rotor-armature, a rotary means for successively elevating the record turn-tables to bring the records thereon into engagement with the stylus of the phonograph, and a driving connection between the rotor-armature and the said elevating means, said driving connection including a clutch device adapted to be set in neutral position and therefore disconnect the elevating means from the driving means.

27. A self-contained motor phonograph including a frame provided with a plurality of sets of motor induction coils, the coils of each set being spaced, a rotor-armature having an armature portion to sweep in the gaps between the spaced coils of the motor magnets, a plurality of record supporting turn-tables, driving means for the turn-tables comprising friction wheels adapted to be individually engaged and driven by a friction driving wheel attached to the rotor-armature, a rotary means for successively elevating the record turn-tables to bring the records thereon into engagement with the stylus of the phonograph, and a driving connection between the rotor-armature and the said elevating means, said driving connection including a clutch device adapted to be set in neutral position and therefore disconnect the elevating means from the driving means, whereby progressive elevating action of the said means is interrupted and any one of the turn-tables may be indeterminately maintained in elevated position while being driven rotatively by the rotor-armature.

28. A phonograph having, in combination, a plurality of record supporting turn-tables arranged in a circle and each being adapted to be shifted from a lower position to an upper position to be engaged by the stylus of the phonograph, a tone arm carrying the stylus and sweeping in a horizontal orbit on a vertical axis at the center of the circle of the turn-tables, orbitally movable means for successively elevating the turn-tables to the effective position, a driving wheel for the turn-tables, a rotating carrier adapted to successively advance the tone arm from one turn-table station to another, and a tone arm arresting means including an annular

member provided with parts adapted to engage the contiguous portion of the tone arm.

29. A phonograph having, in combination, a plurality of record-supporting turn-tables arranged in a circle and each being adapted to be shifted from a lower position to an upper position to be engaged by the stylus of the phonograph, a tone arm carrying the stylus and sweeping in a horizontal orbit on a vertical axis at the center of the circle of the turn-tables, orbitally movable means for successively elevating the turn-tables to the effective position, a driving wheel for the turn-tables, a rotating carrier adapted to successively advance the tone arm from one turn-table station to another, and a tone arm arresting means including an annular member provided with parts adapted to engage the contiguous portion of the tone arm, the arrester being provided with means for preventing reverse motion of the tone arm.
30. A phonograph having, in combination, a plurality of record-supporting turn-tables arranged in a circle and each being adapted to be shifted from a lower position to an upper position to be engaged by the stylus of the phonograph, a tone arm carrying the stylus and sweeping in a horizontal orbit on a vertical axis at the center of the circle of the turn-tables, orbitally movable means for successively elevating the turn-tables to the effective position, a driving wheel for the turn-tables, a rotating carrier adapted to successively advance the tone arm from one turn-table station to another, and a tone arm arresting means including an annular member provided with parts adapted to engage the contiguous portion of the tone arm, the arrester being provided with means for preventing reverse motion of the tone arm as the tone arm is elevated when the stylus thereof is engaged by a record on the uplifted turn-table.
31. A phonograph having, in combination, a plurality of record-supporting turn-tables arranged in a circle and each being adapted to be shifted from a lower position to an upper position to be engaged by the stylus of the phonograph, a tone arm carrying the stylus and sweeping in a horizontal orbit on a vertical axis at the center of the circle of the turn-tables, orbitally movable means for successively elevating the turn-tables to the effective position, a driving wheel for the turn-tables, a rotating carrier adapted to successively advance the tone arm from one turn-table station to another, a tone arm arresting means including an annular member provided with parts adapted to engage the contiguous portion of the tone arm, a power transmitting mechanism connecting the said carrier and the said elevating means, and a driving connection between the said mecha-

nism and the said wheel, and including a clutch device adapted to be thrown into neutral position to cut out the transmitting mechanism from the wheel so that the latter may rotate independently of the said carrier and the said elevating means.

32. In a phonograph having a plurality of record turn-tables arranged in a common circle and in which a stylus and tone arm are adapted to be moved progressively one to the other, means for successively elevating each turn-table, and including an orbitally movable member adapted to engage the stem of each turn-table.

33. In a phonograph having a plurality of record turn-tables arranged in a common circle and in which a stylus and tone arm are adapted to be moved progressively one to the other, means for successively elevating each turn-table, and including an orbitally movable member adapted to engage the stem of each turn-table, said member including a pivotally mounted cam rail.

34. In a phonograph having a plurality of record turn-tables arranged in a common circle and in which a stylus and tone arm are adapted to be moved progressively one to the other, means for successively elevating each turn-table, and including an orbitally movable member adapted to engage the stem of each turn-table, said member including a pivotally mounted cam rail, means for moving the rail to an ineffective position, and means for throwing the rail to an effective position.

35. In a phonograph having a plurality of record turn-tables arranged in a common circle and in which a stylus and tone arm are adapted to be moved progressively one to the other, means for successively elevating each turn-table, and including an orbitally movable member adapted to engage the stem of each turn-table, said member including a pivotally mounted cam rail, means for moving the rail to an ineffective position, means for throwing the rail to an effective position, and means for controlling the restoration of the cam rail to its ineffective position.

36. In a phonograph having a plurality of record turn-tables arranged in a common circle and in which a stylus and tone arm are adapted to be moved progressively one to the other, means for successively elevating each turn-table, and including an orbitally movable member adapted to engage the stem of each turn-table, said member including a yieldingly and pivotally mounted cam rail.

In testimony whereof I have signed my name to this specification.

WILLIAM H. DAILY.
